UNITED STATES PATENT OFFICE.

CHARLES FISCHER, OF NEW YORK, N. Y.

TELEPHONE RECEIVER.

Application filed March 3, 1923. Serial No. 540,699.

To all whom it may concern:

Be it known that I, CHARLES FISCHER, a citizen of the United States, residing at 3657 Broadway, city, county, and State of New York, have invented certain new and useful Improvements in Telephone Receivers, of which the following is a specification.

My invention relates to telephone receivers and particularly to telephone receivers used 10 on head sets for receiving wireless telegraph or telephone messages, more especially the latter.

One of the objects of my invention is to provide a telephone receiver which can be 15 carried on the head of the operator and which can be quickly and cheaply manufactured and the parts assembled correctly and rapidly and in which the magnet can be manufactured of hard steel and fastened into 20 the carrying case without drilling a hole in the magnet, and without altering its magnetic cross section.

With the above and other objects in view, my invention consists in the parts, improvements and combinations more fully pointed out hereinafter.

Referring to the drawings:

Figure 1 is a plan view of the receiver with the diaphragm and cover removed;

Fig. 2 is a vertical cross section on line 2-2 of Fig. 1;

Fig. 3 is a vertical cross section on line 3-3 of Fig. 1;

Fig. 4 is a sectional detail of the means for clamping the magnet and pole piece in registering relation;

Fig. 5 is a detail view of the angle plate carrying a pole-piece and the registering stop for one pole of the magnet;

Fig. 6 is a detail view showing the clamp; and

Fig. 7 is a sectional detail on line 7-7 of Fig. 1.

The parts are mounted in a case 1 which is preferably round and made of brass or non-magnetic material. This case can be attached by ear 2 to the head band. The magnet 3 is U-shaped or arc-shaped, having two poles and is made of hard steel which is cast or bent to fit the case. The magnet is preferably flat-sided.

The receiver coils 4, 5 are connected to the circuit of the wireless receiving system by means of terminal 6, 7 the current entering 50 and leaving the coils by lead wires 8, 9. Each terminal is constructed of a single

metallic plug provided with an aperture 10 into which a lead wire is inserted, being clamped in place by screws 11, 12. The plugs 6, 7 are mounted in sockets or apertures in the insulating block 13 which is secured to the case. Each plug is provided with an annular rim to securely hold the plug in place when molded in the insulating block.

Means are provided for assembling and securing the coils, pole-pieces and magnet in place, in their correct relation, and without drilling holes into the hard steel of which the magnets are made. I provide an angle plate having a soft iron pole-piece 15, there being one plate for each coil and the pole piece forming the core for the coil. The angle plate carries a wing 16 at right angles to the pole piece, the wing carrying a registering stop 17. Each wing is notched at 18, 19 to receive the feet 20, 21 of a removable clamp 22 carrying a clamping lip 23. The clamp is shown inverted in Fig. 6. Screw holes 24, 25 are drilled in the clamp. When the clamp is placed in clamping position the parts assume the position shown in Figs. 1 to 4. After assembling the parts in the case, screws 26 arranged and passing outside of the magnet which pass thru perforations in the back of the case as shown in Fig. 3, enter the holes 24, 25 of the clamp and thus securely fasten the magnet, the pole-pieces and the coils in place, the stops 17 ensuring the correct relation between the position of the magnet ends and the pole-pieces and coils. The magnet does not have to be drilled to provide a means for fastening it in the case and a disturbance of the magnetic circuit and the difficulty of drilling are thus avoided.

The screw cap 27 and sheet metal diaphragm 28 are of the usual construction.

Having thus described the construction and means of assembly, the operation will be clear. When used for a wireless telephone receiver, the coils 4, 5 are wound of fine wire of the necessary high ohmic resistance.

It is understood that the invention is not limited to details and that numerous changes may be made in carrying it into effect without departing from the principle thereof.

What I claim and desire to secure by Letters Patent is:

1. A receiver for wireless receiving systems and the like, comprising the combina-

- tion of a case, a two-pole magnet carried within the case, a pair of coils, a pair of angle plates, the upturned ends of which form cores for the said coils, said plates having 5 wings at right angles to their ends upon which wings the magnet arms rest, each of said wings provided with a pair of notches, removable clamps each having a lip engaging the side of the magnet and each clamp 10 provided with a pair of feet entering the notches, said feet provided with screw-holes and screws for removably securing said feet to the case.
2. A receiver for wireless telephone receivers and the like, comprising the combination of a case, a two-pole magnet carried within the case, a pair of coils, a pair of plates one for each pole of the magnet, each plate having a portion forming the core of 15 one of said coils, and each plate provided with a wing carrying a stop for one pole of the magnet, removable clamps each having a lip engaging the side of the magnet and means for removably securing said clamps 20 to said case.
3. A receiver for wireless receiving systems and the like, comprising the combination of a case, a two-pole magnet carried within the case, a pair of coils, a pair of angle plates, the upturned ends of which form cores for the said coils, said plates having wings at right angles to their ends upon which wings the magnet arms rest, each of said wings provided with a pair of 25 notches, and each of said wings having a bent portion forming a stop for the end of the magnet, removable clamps each having a lip engaging the side of the magnet and each clamp provided with a pair of feet entering said notches, said feet provided with screw-holes and screws for removably securing said feet to the case.
4. A wireless telephone receiver comprising a casing, a two-pole magnet, and a telephone coil, a detachable bent right-angled plate of soft iron having one limb forming the core for said coil, the other limb having a bent portion forming a stop for the corresponding end of the magnet and means 30 for removably securing said magnet and plate to the casing.
5. A magnetic receiver for wireless receivers and the like, comprising the combination of a case, a magnet carried within the case, said magnet having two ends forming the poles thereof, a pair of coils, a pair of separate detachable pole plates of magnetic material one for each pole of the magnet, each plate having a portion forming the core of one of said coils and another portion 55 upon which the corresponding end of the said magnet rests, a detachable plate having a portion engaging the side of the magnet, said latter plate and one of said pole plates embracing the magnet end between them, a 60 stop for one pole of the magnet carried by one of said plates, and means passing outside of the magnet, detachable from said plates for removably securing said plates to said magnet and to said case. 65
6. A magnetic receiver for wireless receivers and the like, comprising the combination of a case, a magnet carried within the case, said magnet having two ends forming the poles thereof, a pair of coils, a pair of 70 separate detachable pole plates of magnetic material, one for each pole of the magnet, each plate having a portion forming the core of one of said coils, and a portion on which the end of the magnet rests, a removable clamping plate engaging the side of the magnet, said removable plate providing clamping means for clamping the magnet to the casing, a stop for one pole of the magnet carried by one of said plates and means 75 passing outside of the magnet, detachable from said plates for removably securing said magnet to said case. 80
7. A magnetic receiver for wireless receivers and the like comprising the combination of a case, a magnet carried within the case, a pair of plates, one of them a pole plate, the other a clamping plate, between which the magnet is arranged, a stop for one pole of the magnet carried by one of 85 said plates, and a screw passing outside of the magnet for securing the magnet to the case. 90

In testimony whereof, I have signed my name to this specification.

CHAS. FISCHER.
